UNITED STATES PATENT OFFICE.

JOSEPH I. HERBERT, OF CHICAGO, ILLINOIS.

HEATING APPARATUS.

1,416,025.

Specification of Letters Patent. Patented May 16, 1922.

Application filed July 29, 1920. Serial No. 399,867.

To all whom it may concern:

Be it known that I, JOSEPH I. HERBERT, a citizen of the United States, residing at Chicago, in the county of Cook and State 5 of Illinois, have invented certain new and useful Improvements in Heating Apparatus, of which the following is a specification.

This invention relates to improvements in heating apparatus, and has provided an electrically heated vapor or steam-generating apparatus which may be used as a unit with 10 a single radiator or the like, or which may be applied to a battery of radiators, if so desired.

15 An object of my invention is to provide such a heating unit in which the minimum amount of water subjected to heating is maintained approximately constant, thereby permitting the use of a minimum body of 20 water and accomplishing the desired heating effect with the use of a minimum amount of electric current.

Another object resides in the provision of 25 means to impart a preliminary heating to the incoming water.

Still another object resides in the provision of the various details of construction; and other objects will be more fully set forth and described in the following specification 30 and shown in the accompanying drawing, in which—

Figure 1 is a vertical section of an apparatus embodying my invention; and

Fig. 2 is a side elevation of a radiator 35 showing my apparatus applied thereto.

Like numerals denote like elements throughout the drawing, in which—

10 indicates a casing which is, in effect, a tank in which is maintained a body of 40 water 11. An inlet pipe 12 extends through the casing, terminating in the upwardly curved elbow 12^a normally submerged beneath the body of water. A nipple 13, having a wrench engageable portion 13^a, is 45 threaded into engagement with the elbow 12^a and is provided with a central aperture 13^b terminating at its upper end in the valve seat 13^c. The tube 14 is threaded to the upper end of the nipple 13, being provided 50 with outlet ports 14^a adjacent its lower portion. Adjacent its upper portion the tube 14 is provided with opposed pairs of spaced lugs 14^b, between each pair of which is pivoted an arm 15. The arms are pivoted on the pin 16 or the like and carry enlarged 55 or ball-shaped portions 15^a at their outer

extremities. At their inner extremities 15^b the arms 15 engage the spaced apart peripheral flanges 17^a of the sleeve 17, which, in turn, surrounds the valve stem 18^a, carrying 60 at its lower extremity the valve 18 normally seating on the seat 13^c. The stem 18^a is threaded at 18^b at its upper extremity, and a rotatable nut 19 engages such threaded portion to adjust the position of the valve 65 as desired. Surrounding the tube 14, to vertically reciprocate free thereof, is the hollow float or buoy 20, upon the tube of which rest the ball portions 15^a of the arms 15.

The casing or tank 10 is provided with a 70 suitable aperture 10^b in the bottom thereof, through which projects the casing 25, within which is located an electric heating coil 26 mounted on a core 27 of asbestos, bakelite, or other suitable insulating material. The 75 casing is formed with a peripheral flange 25^a resting upon a gasket 28. The casing is further threaded at its lower portion 25^b, which projects downwardly from the tank 10, a nut 29 engaging this threaded portion 80 to draw this flange 25^a into proper engagement with the gasket to prevent leakage. The terminals 26^a and 26^b of the electric heating coil lead to the sockets 30, in which 85 may be plugged the terminals 31^a of the plug 31 carried by the main feed wire 32.

At one side of the casing 10 is provided an inlet opening 10^c, suitably communicating with which is return pipe 33 having a flange 33^a and a threaded extremity 33^b engaged 90 by the nut 34. The pipe and union, generally indicated by 36, is coupled to pipe 33 and leads to the boss 37^a carried by the radiator 37, which is shown as of conventional construction. The tank 10 is provided with 95 a cover 10^d threadable into closing position, a gasket or packing ring 40 being located between the cover and tank to prevent leakage of gas or fluid. The cover is provided with an outlet duct 10^e, which, in turn, communicates with a steam or vapor pipe 41 leading to the upper portion of the radiator 37.

In the operation of my device, when the terminals 31^a fit in the sockets 30 and current flows through the coil 26, consequent heating of the body of fluid will result, and steam or vapor will be generated, which will flow through the pipe 41 into the radiator 37. As this steam is condensed, it will 105 return to the body of fluid 11 beneath the upper level thereof, thereby maintaining a 110

short circuit of travel, and a consequent increase in efficiency of heating.

To replace the relatively small amount of fluid utilized in this heating operation, the 5 float 20 will function to permit dropping of the ball ends 15^a of the arms 15 upon a lowering of the fluid level in the tank 10. This movement of the arms results in the 10 raising of the sleeve 17 and lifting of the valve 18 from the seat 13^c, whereupon fluid will be supplied through inlet 12 into the tank through the apertures 14^a. The elbow 12^a and pipe 12, being heated from immersion in the body of fluid 11, will pre-heat 15 the incoming fluid, thereby increasing the efficiency of the apparatus.

As soon as the supply of fluid reaches the desired level the fluid 20 will raise the balls 15^a, thereby closing the valve 18 and cutting off further flow.

As illustrated in Fig. 2 of the drawings, I am enabled to apply individual heating units to each radiator, with consequent great increase in efficiency over present-day apparatus, thereby greatly decreasing the cost 25 of heating and the amount of fluid utilized.

It will be obvious that my invention is susceptible of numerous improvements and 30 modifications, and I do not therefore wish to be restricted thereto, except as defined in the appended claims.

I claim:—

1. In apparatus of the class described, 35 comprising a radiator, a steam supply pipe, and a condensation exhaust pipe leading to and from said radiator respectively, a tank located adjacent said radiator, said supply and exhaust ducts leading from and to said 40 tank respectively, a heating unit located in said tank, means to supply fluid to said tank, and means to maintain the level of said fluid constant.

2. In apparatus of the class described a 45 heating unit comprising a tank, a heating member located therein to heat the contents thereof, a fluid supply duct extending into the interior of said tank, a valve normally closing said duct, and means actuated by 50 the fluid in said tank to close or open said valve.

3. In apparatus of the class described, a heating unit comprising a tank, an electric heating element located therein, means to supply fluid to said tank, and means to maintain the level of said fluid constant, said last-named means comprising a float, an adjustable reciprocable valve and arms actuatable by said float and operably engaging said valve. 55

4. In apparatus of the class described, a heating unit comprising a tank, a heating element comprising an encased electric heating coil projecting into said tank, and means to supply fluid to said tank after preheat- 60 ing by said heating element.

5. In apparatus of the class described, a heating unit comprising a tank, a heating element comprising an encased electric heating coil projecting into said tank, and means 65 to supply fluid to said tank, said tank being provided with a return duct opening thereinto below the fluid level of said tank and a vapor outlet duct.

6. In apparatus of the class described, a 75 heating unit comprising a tank, a heating element comprising an encased electric heating coil projecting into said tank, and means to supply fluid to said tank, said tank being provided with a return duct opening there- 80 into below the fluid level of said tank and a vapor outlet duct, said tank being provided with a sealing cover.

7. In apparatus of the class described, a heating unit comprising a tank, a heating 85 element located therein to heat the contents thereof, means to supply fluid to said tank, said means comprising a supply duct located in said tank beneath the fluid level thereof whereby the inflowing fluid is preheated. 90

8. In apparatus of the class described, a heating unit comprising a tank, a heating element located therein to heat the contents thereof, means to supply fluid to said tank, said means comprising a supply duct located 95 in said tank beneath the fluid level thereof, and means to maintain such fluid level approximately constant.

In testimony whereof, I have subscribed my name.

JOSEPH I. HERBERT.
